Patented Mar. 18, 1975

234,522

BIRD FEEDER

James C. Fry, Wooster, Ohio, assignor to Rubbermaid
Incorporated, Wooster, Ohio

Filed May 18, 1973, Ser. No. 361,798

Term of patent 14 years

Int. Cl. D30—03

U.S. Cl. D30—13

FIG. 1

FIG. 2

FIG. 3

FIG. 4

FIG. 5

FIG. 1 is a top plan view of a bird feeder embodying my new design.

FIG. 2 is a front elevational view, the rear elevational view being a mirror image thereof.

FIG. 3 is a side elevational view.

FIG. 4 is a top plan view thereof with the roof removed.

FIG. 5 is a cross-sectional view along the line 5—5 of FIG. 1.

I claim:

The ornamental design for a bird feeder, as shown and described.
